SUBSTITUTE FOR TIN HORMS

John Elwood Wilson, Watsontown, Pa.

Application May 31, 1944, Serial No. 538,181

3 Claims. (Cl. 46—181)

The invention relates to a toy horn, and more particularly to a non-metallic sound producing instrument, such as a horn, trumpet or the like.

The primary object of the invention is the provision of an instrument of this character, wherein the sound reed is non-metallic, thus increasing the life of the instrument, the construction of the latter being such as to materially increase the sounding quality thereof.

Another object of the invention is the provision of an instrument of this character, wherein the body and mouthpiece thereof are devoid of metal, and in the construction of the mouthpiece, it may be equipped with single or double reeds, these being non-metallic to give greater lasting qualities to the instrument, as they will not become unduly bent or broken through careless handling or otherwise.

A further object of the invention is the provision of an instrument of this character, which is simple in construction, thoroughly reliable and efficient in the working thereof, assured of maximum sounding quality, neat in appearance, strong, durable, light in weight, possessing few parts, readily and easily operated, and inexpensive to manufacture.

With these and other objects in view, the invention consists in the features of construction, combination and arrangement of parts as will be hereinafter more fully described, illustrated in the accompanying drawings, which disclose the preferred and modified forms of construction of the invention, and hereinafter pointed out in the claims.

In the accompanying drawings—

Figure 1 is a side view, partly broken away, of the instrument constructed in accordance with the invention.

Figure 2 is an end elevation thereof.

Figure 3 is a plan view of one of the throat wedges or reed holding keys. Figure 4 is a side view thereof. Figure 5 is a perspective view of the throat di-

Figure 6 is a perspective view of the vibrator.

Figure 7 is a view similar to Figure 1 showing a diSection.

Figure 8 is a sectional view taken on the line 8—8 of Figure 7 looking in the direction of the arrows.

Figure 9 is a plan view of one of the throat parts of the reed carried thereby.

Figure 10 is a plan view of a dividing plate for twin reed throat core.

Figure 11 is a perspective view of the centering ring for the reed core and dividing plate.

Figure 12 is a fragmentary side view partly in section of a further modification of instrument.

Figure 13 is an end sectional view thereof, taken on the line 13—13 of Figure 12.

Figure 14 is a perspective of a retaining plug for the single reed throat core in Figure 13.

Similar reference characters indicate corresponding parts throughout the several views in the drawings.

Referring to the drawings, in detail, particularly Figures 1 to 6, inclusive, A designates generally the instrument constituting a horn or trumpet constructed in accordance with the invention, and comprises a substantially conical shaped shell or

body 10, preferably made from fibrous material, thus being non-metallic, having at its smaller end a matching non-metallic mouthpiece 11, these being adhesively joined with each other, so that the external surfaces of both will be flush with one another.

Interiorly of this mouthpiece 11 is a throat cor including a central dividing plate 12 having in opposite faces thereof outwardly tapered air channels or air courses 13, which terminate slightly

ly removed from the outer end of the said plate, gradually increasing in size therefrom and opening through the inner end of such plate. Next to these channels 13 and co-extensive therewith are the thin tongue-like vibrating reeds 14, preferably made from Celluloid or mica, and each is of outwardly tapering formation, the innermost end of the reed being slightly bent back at 15.

ends of these reeds being adhesively taped at 15 to the dividing plate 12, which tape 15 is carried about the said plate and overlies the reeds, while in abutting relation to the taped reeds 14 and the dividing plate 12 are throat core wedging or holding bars 16 that are attached to the dividing

holding keys 16, these together with the said plate 12 and reeds 14 are outwardly tapered. The keys 16 and the dividing plate 12 effect the sectional throat core and the keys securely fastened the reeds 14 and the plate 12 in place within the mouthpiece 11.

In Figures 9 to 11, inclusive, of the drawings, there is shown a modification of the instrument, wherein the throat core involves the outer substantially half-circular shaped core sections 17, and the intermediate dividing plate 18, respectively, the latter separating the air channels or air courses 19, formed in the same sections 17, while next to such channels or courses 19 are the vibrating reeds 20, which are tapered at 21 to the sections 17, these together with the plate 18 being encircled by a centering ring 22, which

wedges the inner end of the core at its inner end centered within the mouthpiece 23 made from non-metallic material. The core and the reeds are made from non-metallic material. The mouthpiece 23 is provided with a mouth engaging tip 24 having an external lip abutment 25 thereon.

In Figures 12, 13 and 14 of the drawings, there is shown another modification of the invention, wherein the mouthpiece has within a single reed equipped throat core, involving the section 26, which is similar to one of the sections 17, with the reed 27 taped thereto at 28, and this section and reed are centered in the mouthpiece by a ring 29, and held therein by a half-circular wedge plug or key 30, which is superimposed on the plate 31 identical to the plates 12 and 18, respectively, hereinbefore set forth. The section 26 has the air channel or air course 32 formed therein.

In the use of the instrument A by blowing through the mouthpiece thereof the single or twin reeds within are vibrated for the sounding thereof.

The constructions of the instrument as hereinbefore described avoid the use of metal, and enables it to be manufactured at a minimum cost, as well as being strong and durable, with increased noise producing effect.

What is claimed is:

1. A horn of the kind described, comprising a conical shaped non-metallic body, a mouthpiece of non-metallic material joined with the body at

its smaller end, a sectional non-metallic throat core within the mouthpiece and having a dividing plate fitted therewith, the throat core being an air course through the mouthpiece, and tongue-like non-metallic sound producing means in the throat core and intercepting the air course.

5 2. A horn of the kind described, comprising a conical shaped non-metallic body, a mouthpiece of non-metallic material joined with the body at its smaller end, a sectional non-metallic throat core within the mouthpiece and having a dividing plate fitted therewith, the throat core being an air course through the mouthpiece, tongue-like non-metallic sound producing means in the throat core and intercepting the air course, and means for centering the throat core within the mouthpiece.

10 3. A horn of the kind described, comprising a conical shaped non-metallic body, a mouthpiece of non-metallic material joined with the body at its smaller end, a sectional non-metallic throat core within the mouthpiece and having a dividing plate fitted therewith, the throat core being an air course through the mouthpiece, tongue-like non-metallic sound producing means in the throat core and intercepting the air course, and means for centering the throat core within the mouthpiece, and adhesive tape affixing the sound producing means in place in the core.

20 JOHN ELWOOD WILSON.
